United States Patent Office

Des. 181,904
Patented Jan. 14, 1958

181,904

EAR CLIP OR SIMILAR ARTICLE

Hans J. Feibelman, Providence, R. I., assignor to Coro
of Rhode Island, Inc., Providence, R. I., a corporation of Rhode Island

Application April 18, 1957, Serial No. 45,791

Term of patent 14 years

(Cl. D45—9)

Fig. 1

Fig. 2

Fig. 3

Fig. 5

Fig. 1 is a front elevational view of an ear clip or similar article embodying my new design;

Fig. 2 is a side elevational view;

Fig. 3 is a rear elevational view;

Fig. 4 is a top plan view; and

Fig. 5 is a bottom plan view thereof.

I claim:

The ornamental design for an ear clip or similar article, substantially as shown.
